UNITED STATES PATENT OFFICE.

VICTOR H. JENNINGS, OF WORCESTER, MASSACHUSETTS, ASSIGNOR TO UNIVERSAL PATENTS COMPANY, OF WOONSOCKET, RHODE ISLAND, A CORPORATION OF RHODE ISLAND.

MACHINE-GUN BELT AND OTHER LIKE CARRIER.

1,257,241.

Specification of Letters Patent. Patented Feb. 19, 1918.

Application filed April 19, 1917. Serial No. 163,216.

To all whom it may concern:

Be it known that I, VICTOR H. JENNINGS, a citizen of the United States, residing at Worcester, in the county of Worcester, State 5 of Massachusetts, have invented a certain new and useful Improvement in Machine-Gun Belts and other like Carriers, of which the following is a specification, reference being had therein to the accompanying drawings.

The invention is an improvement in machine-gun belts and other carriers of the same general character as those used as machine-gun belts. It consists in a belt or 15 carrier having transverse loops to receive and contain cartridges, etc., and having a continuously divided or split margin or selvage at one or both sides thereof. The general aim of the invention is to facilitate 20 the operations by which a belt or carrier is loaded. The principle of the invention may be embodied variously in practice, and in belts or carriers of various constructions. The drawings show several different em- 25 bodiments thereof.

In the case of a machine-gun belt or carrier the continuously divided or split margin or selvage serves especially for facilitating the entrance of the loop-opening 30 "needle" of a loading machine, or the entrance of the cartridges themselves, or of both, into the successive loops of a belt or carrier, and for insuring such entrance without failures or mal-functions in the loading 35 operation, and without injury to the belt or carrier by the point of the needle or the points of the bullets of the cartridges. It also enables beaded margins or selvages to be dispensed with, when desired, in the case 40 of woven belts or carriers.

Figure 1 of the drawings is a perspective view of a belt or carrier woven in one piece and having a slitted or divided margin or selvage at the side at which the bullets of 45 the cartridges project, with cartridges occupying some of the loops of the said belt or carrier.

Fig. 2 is an edge view of the woven belt or carrier of Fig. 1.

50 Fig. 3 is a perspective view showing a belt or carrier comprising two flexible strips or webbings fastened together by means of clips.

Figs. 4 and 5 are perspective views illus-

trating belts or carriers having slitted or divided margins or selvages at the side at which the cartridges enter the loops.

Fig. 6 is a perspective view showing a belt or carrier having slitted or divided margins or selvages along both sides thereof. 60

The belt or carrier of Fig. 1, woven in one piece, comprises a woven web which is made in separate plies 1, 1, at intervals to produce the loops which receive and contain the cartridges 2, 2. In the case of other carriers besides machine-gun belts, the loops will be adapted to receive such other articles as the belt or carrier is designed to have applied thereto. Between the loops the two plies are united or combined as at 3, 3. In 70 carrying the invention into effect in the manufacture of such belt or carrier, the said plies are not united or combined across the entire width of the web, but are woven dis-united or separate for a short distance trans- 75 versely of the web at the margin of the latter at which provision for the desired re-sults should be made. In this instance it is at the margin at which the bullets 2^a, 2^a, of the cartridges project. Thereby the belt or 80 carrier is produced with a margin 4, 4, which is continuously slitted or divided in thickness longitudinally; in other words, the belt or carrier is produced with what may be termed a continuously divided or longitudinally slitted margin or selvage 4, 4. The two sides of this margin or selvage are adapted to be spread apart or separated readily, to admit between them the point of the needle of a machine for automatically 85 loading the belt or carrier with cartridges or other articles. The said point, after enter-ing between the said sides, will pass readily into the loop which has been presented in line with the needle. The separated sides 90 act as guides to facilitate the entrance of the needle-point or end into such loop.

One contemplated purpose of the divided or longitudinally slitted margin or selvage is to furnish a channel to receive a plow or 100 channel-opener in connection with the loading machine, arranged to occupy the chan-nel in advance of where the loop-opening needle operates, so that as a belt or car-rier is fed past the loading devices the said 105 plow or channel-opener, by reason of occu-pying the channel, shall serve to spread apart the sides of the longitudinally slitted

or divided margin or selvage for the ready admission and guidance of the needle into each of the loops in succession as they are presented in position to be entered.

5 The belt or carrier of Fig. 3 is in the main of a well-known type of construction comprising two strips 5, 5, of flexible material, preferably woven strips or webbings of the proper width for the belt or carrier, placed 10 face to face and bound together, at intervals determined by the size of the required loops (by means of pairs of metal clips 6, 6, the two clips of a pair being placed against opposite sides of the two strips or webbings 15 and being fastened together by means of hollow rivets or eyelets 7, 7. In Fig. 3 the said clips are of such length that they terminate at a suitable distance from the edges of the strips or webbing, at the margin which is required 20 to be left split or divided, to leave the marginal portions 4^a, 4^a, of the two strips or webbings unbound and capable of being spread apart, as indicated in Fig. 3. The said marginal portions 4^a, 4^a, serve the same 25 useful functions as those marked 4, 4, in Figs. 1 and 2.

Ordinarily in practice heretofore, at the side of a machine-gun belt or carrier at which the loop-opening needle of the loading machine enters the loops, the strip or strips constituting the body of the said belt or carrier has or have been woven with enlarged or beaded selvages, to facilitate the insertion of the point of the said needle between 30 the two sides of a loop. These enlarged or beaded selvages add to the cost of the strip or strips. The invention enables them to be dispensed with, if desired, as in the case of the various belts or carriers 35 shown in the drawings.

Figs. 4 and 5 show the edge of the belt or carrier at which the cartridges are introduced slitted or divided longitudinally, producing the divided margin or selvage 4^b, 4^b, 40 or 4^c, 4^c. When the belt or carrier is thus

slitted or divided along the said edge, the insertion of the cartridges point first into the respective loops is facilitated in the same manner and respects as explained with reference to the insertion of the loop-opening 50 needle at the other edge. Fig. 4 shows a woven one-piece web as in Figs. 1 and 2. Fig. 5 shows a belt or carrier comprising two strips or webbings bound together by clips, 6^a, 6^a, and rivets 7^a, 7^a, substantially as 55 in Fig. 3, but with the clips terminating at a distance from the top edge of the belt or carrier corresponding with the desired width of slit. Fig. 6 shows both edges of the belt or carrier longitudinally slitted or divided, 60 at 4^d, 4^d, and 4^e, 4^e, to facilitate the introduction of the loop-opening needle into the loops at one edge, and the insertion of the cartridges at the other.

What is claimed as the invention is,—

1. A machine-gun belt or the like carrier having transverse loops to receive cartridges, etc., and having a continuously divided or split margin or selvage.

2. A machine-gun belt or the like carrier 70 having the opposite sides of its loops bound together between loops but disunited for a part of the width of the belt or carrier to form a continuously divided or split margin or selvage.

3. A machine-gun belt or the like carrier comprising a web formed, as woven, with transverse loops and having the sides of such loops joined together, in the weaving, across a portion of the width of the carrier but left 80 disunited for a second portion of the said width to form a continuously divided margin or selvage.

In testimony whereof I affix my signature in presence of two witnesses.

VICTOR H. JENNINGS.
